UNITED STATES PATENT OFFICE

AARON K. VERNON, OF FLUSHING, NEW YORK

ADVERTISING CLOCK.

Application filed July 18, 1931. Serial No. 551,741.

This invention relates to an advertising clock and especially to an electric advertising clock and has for an object to provide a combination clock and advertising sign 5 wherein the operation of the clock works will keep the sign in motion to continuously present new advertising matter visible thereon.

A further object of this invention is to provide an attractive advertising medium for a store, store window, or the like, wherein advertising matter may be continuously and effectively brought to the attention of the public at the same time that their attention 15 has been attracted by the clock for the purpose of informing them of the correct time.

Another object of this invention is to provide an endless advertising belt kept in continuous operation by the works of a clock 20 which works may be of any type although the preferred form is that of the electrical type of clock, thereby avoiding the necessity of rewinding the clock works.

Still another object of this invention is to provide a simple and effective combined unit which may be made in several forms.

With the foregoing and other objects in view, as will hereinafter become apparent, this invention comprises the constructions, 30 combinations, and arrangements of parts, hereinafter set forth, claimed and shown on the accompanying drawings. In the drawings,

Figure 1 is a perspective view of one form 35 of this invention.

Figure 2 is a cross sectional view on line 2-2 of Figure 3, being a cross section just behind the front face of the combined unit.

Figure 3 is a cross section on line 3-3 of 40 Figure 2.

Figure 4 is a cross section on line 4-4 of Figure 2.

Figure 5 is a detailed cross section on line 45 5-5 of Figure 4.

Figure 6 is a perspective view of the detail 50 of the spool supporting bracket.

Figure 7 is a perspective view of another 55 form of this invention.

Figure 8 is a sectional view on line 8-8 of 60

Figure 9, being a cross section view behind the front face of the unit.

Figure 9 is a section on line 9-9 of Figure 8.

Figure 10 is a section on line 10-10 of Figure 55 8.

Figure 11 is a perspective of the shaft lock.

Figure 12 is a broken perspective view of the shaft bracket shown in Figure 8.

Figure 13 is yet another form of this invention. 60

Figure 14 is a front view of this form of the invention with the front face removed.

Figure 15 is a broken section on line 15-15 of Figure 14.

Figure 16 is a section on line 16-16 of Figure 65 14.

Figure 17 is an enlarged view of the shaft and gearing shown in Figure 14, and

Figure 18 is a perspective sectional view 70 of the gear rod and holder.

There is shown at 20 the combined clock and advertising unit having clock face 21 and advertising exhibit 22. The clock face 21 has the hands 23 operated by a shaft 24 75 which shaft in turn is operated by conventional clock works not shown. At 25 is shown an electric conductor whereby to supply power for operating the clock works when the same are electric which is the preferred form, although it will be understood that any type of clock works may operate this clock. A gear 26 is operated by one of the gears of the clock works whether electrical or otherwise and through its shaft 27 80 operates gear 28. Gear 28 is connected from a train of gears 29 to a gear 30 which operates a spool 31.

Passing about the spool 31 and a pair of oppositely disposed spools 32 affixed within the unit 20 is an endless belt 33, the spools 32 being affixed within the unit 20 by means of the bracket 34.

As will be apparent from Figure 2, the endless belt or tape 33 has its flat surface horizontal and on this surface is printed or painted advertising matter in reverse as shown at 35. This entire spool and tape arrangement is completely concealed behind the front 36 of unit 20, there being an open- 100

ing 37 in a horizontal ledge 38. Directly below this opening is a reflecting mirror 39 affixed to the bottom of the unit 20, as at 40.

The operation is as follows:

- 5 The clock is started going either by connecting up the conductor 25 to a source of power in the usual manner, or by winding the clock works with the spring type as used and the hands set at the proper time.
- 10 Through the gear 29 the spool 31 will be kept in continuous operation, thereby causing the endless belt or tape 33 to revolve continuously. The speed of revolution of this belt can be determined by selecting the proper ratio of gears in the train 29 so that the belt may be revolved at the desired speed. The belt which is set horizontal will revolve over the reflecting mirror 39 so that when viewed from the front of the clock only the advertising matter 35 will appear to the observer, which will be right side up and legible as shown in Figure 1, due to the angle at which the mirror is set.

All of the clock works and spool arrangements for holding the belt 33 will be invisible inasmuch as they are concealed beyond the ledge 37 and will not show through the mirror. The form shown in the combination unit 41 in Figures 7 to 12 differs from that shown in Figures 1 to 7 by a different placement of the advertising belt 42 which, due to said different placement will have its advertising matter 43 printed or painted right side up and visible 30 through the opening 44 in the front 45 of unit 41, the spools 46 being concealed behind the ledges 47. In this form the trained gears 48 are operated by the gear 49 connected to the clock works and in turn operating the bevelled gear 50 and through shafts 51 and 56 to turn spool 52 through its bevelled gear connections 53, the shaft 51 being supported by the bracket 54 and the annular bracket 55. The angular bracket 55 in turn supports the horizontal shaft 56 on which the bevelled gear 50 is placed.

In the form shown in the combined unit at 60, the endless belt 61 operates vertically and has its advertising matter 62 thereon. The belt 61 passes about spools 62 and 63 which are journaled on spindle 64 and 65. The spindle 65 has thereon a gear 66 operated by the gear 67 on shaft 68, thus as the shaft 68 is rotated the spool 62 will be rotated by its spindle 65, thereby rotating the advertising belt 61 at the desired speed, it being noted that the operative mechanism is concealed behind the ledges 69 through the opening of the front face 70.

60 A bevelled gear 71 on shaft 68 is operated by a beveled gear 72 on shaft 73, the shaft 73 being journaled to the bracket 74 and having a beveled gear 75 at its other end operated in turn by a beveled gear 76. The beveled gear 76 is affixed on stub shaft 77

having thereon a gear 78, which in turn is operated by a training gear 79. The training gear 79 is connected for operation to the clock works in a manner similar to that shown in the first two forms.

Without further description, it is thought that the novel features and advantages inherent in the invention will be readily apparent to those skilled in the art, it being understood that changes in the form, proportion and minor details of construction may be resorted to, without departing from the spirit of the invention or its scope as claimed.

Having thus set forth and disclosed the nature of this invention, what is claimed is:

1. A combination clock and advertising unit comprising a clock and display casing, a clock mechanism centrally of said casing, an advertising display located below said clock mechanism, said advertising display comprising an endless belt, a pair of rollers, each of said rollers being mounted at opposite sides of said display casing, a third roller centrally of said casing, said endless belt passing over said three rollers, and a gear train connecting said third roller to said clock mechanism for rotating said belt.

2. A combination clock and advertising unit comprising a clock and display casing, a clock mechanism centrally of said casing, an advertising display located below said clock mechanism, said advertising display comprising an endless belt, a pair of rollers, each of said rollers being mounted at opposite sides of said display casing, a third roller centrally of said casing, said endless belt passing over said three rollers, a gear train connecting said third roller to said clock mechanism for rotating said belt, inverted advertising matter on said belt, and an angular mirror mounted in said display casing below said belt to visibly display in upright position the advertising matter on said rotating belt.

In testimony whereof I affix my signature.

AARON K. VERNON.
